UNITED STATES PATENT OFFICE

EDMUND W. DEAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN

TUBULAR-PLATE PRESS AND FOLDER

Application filed July 2, 1928. Serial No. 289,841.

This invention is an improvement in web printing and folding presses and has particular reference to single-page tubular-plate presses of the type disclosed in Bechman Patent No. 867,230, dated October 1st, 1907, in which each plate cylinder carries two tubular single-page plates and prints upon a two-page wide web.

These so-called "tubular" presses operate on the so-called straight line principle, and print duplicate consecutive impressions upon the web so that no "collecting" is ever required.

The present invention is especially designed for use in connection with "tubular" presses having three or more decks and capable of printing 24 or more newspaper pages at each operation. Heretofore such presses have sometimes been provided with two folders so that they could print and deliver two papers simultaneously in book fold; also heretofore two folders have been arranged one above the other to enable two book fold papers to be delivered simultaneously from one such press. With such a superposed arrangement of folders one group of webs after passing the former of one folder could be led to the first fold rolls of the other folder so that a single paper would be delivered in two "sections" by the latter folder.

Also heretofore two such tubular presses have been arranged side by side each with a folder, so that each might deliver a paper in book fold; or the webs from one press after passing the former of its folder could be led over to and associated with the webs passing the former of the other folder, and delivered as one large paper in two sections. The use of a plurality of folders involves considerable expense; and to arrange two folders or formers one above the other necessitates a great deal of head room in the press room, and also requires the pressman to climb up on a platform to get access to the upper folder or former in threading webs thereto.

The two-page wide tubular presses heretofore made with one folder could not deliver any product in sections; while an ordinary semi-circular plate press equipped with duplicate plates and one folder can deliver a newspaper book fold up to full capacity,

without collecting; or if equipped with non-duplicate plates and "collecting" can deliver papers in sections but at much less speed.

Tubular plate presses cannot use duplicate page plates and therefore cannot use any "collecting" means in the folder; and consequently a tubular plate press with a single folder cannot deliver papers in sections unless there is provided either an additional folder, or an additional former placed above the former of the regular folder. In many places where such presses are to be installed there is not sufficient head room to permit the use of an extra former or an extra folder superposed above the other; and to provide duplicate folders adds materially to the cost of the outfit.

The object of the present invention is to enable a single width tubular page press, using single plate only, to deliver its product either in book fold or in sections, without requiring any additional head room in the press room, and without necessitating the employment of two folders.

In accordance with my invention I provide means whereby part of the webs coming from the press may be deflected laterally to and over a former placed at one side of the press folder, in such position that the webs after passing such former may be led back to the folder and be assembled with the webs passing the former of such folder; thus enabling papers to be delivered in "sections" if desired—or all the webs can be led direct to the folder and the papers be delivered in book fold if desired.

In my invention no additional head room is required, and the pressman can thread all the webs from the press to and through the folder from the floor, and any desired number of pages can be delivered from the folder in book fold; or by running part of the webs over the auxiliary former papers can be delivered in sections.

To enable others to fully understand and use the invention I will explain the same with reference to the accompanying drawings in which:

Figure 1 is a side elevation of a portion of an ordinary 24-page two-page wide tubular

plate press and folder, equipped with my attachment to enable it to deliver papers in sections.

Figure 2 is an end view of Fig. 1.

Figure 3 is a diagrammatic top plan view of such press and folder.

The tubular plate press may be constructed as described in the aforesaid Bechman patent; a 24 page tubular press of this type 10 would have three decks, each of which decks contains two perfecting mechanisms each comprising two plate cylinders P and two impression cylinders I, and inking mechanisms (not shown). Each plate cylinder P 15 is adapted to carry two tubular single page plates; and each perfecting mechanism will print four pages on a web. There are two such perfecting mechanisms in each deck, but only one set of perfecting mechanisms in each 20 deck is indicated in Figure 1 of the drawings.

Two webs w' and w^2 are printed on the lower deck; two webs w^3 and w^4 are printed on the middle deck; and two webs w^5 and w^6 25 are printed on the upper deck. Each of these webs may be led over suitable guides, as indicated in Fig. 1, directly to the roller A at the top of the former F of a folder which is arranged directly in line with and at one end of 30 the press; so that each of the webs can be run in a straight line from its web roll to and through the related printing mechanism and to and over former F, and be directed thereby between the first fold rollers B; and thence 35 between the usual cutting cylinders C and D, and be severed and the papers ejected between the second fold rolls (not shown) of usual construction; the product of the press when the webs are thus assembled being papers delivered in book fold.

The particular construction of the folder forms no part of the present invention. It may be of ordinary or any desired construction, except that no collecting devices are employed—further explanation thereof is unnecessary.

The tubular press and folder so far described are well known and will deliver "book fold" papers of any size up to the full capacity of the press.

To enable such a two-page wide tubular plate press to deliver papers in "sections" when desired, I provide guides whereby some of the printed webs can be directed over a set 55 of angle bars 2, 3 and 4 arranged between the press and folder at an angle of 45° to the roller A; and then over a second set of angle bars 2^a, 3^a and 4^a arranged at one side of the press parallel with the rollers 2, 3 and 4 and adjacent a roller A' at the upper end of an auxiliary former F', which may be mounted in a frame 5 at one side of the folder; and a pair of first fold rolls B' are provided adjacent the apex of former F'. The rolls B' may be driven by a train of gears 6^b driven by

bevel gears 6^a from a shaft 6; which may be driven by gears 6^c from the shaft of roll C; the gearing is such that the rolls B' will be driven in unison with the first fold rolls B.

The roller A' may be driven by a train of gears 7^a from the same shaft 7^b which through gears 7^a drives the roller A. The gearing for driving the roller A and first fold rolls B of the folder forms no part of the present invention; but the shafts 6 and 7 of the folder 75 can be extended as shown; and actual gearing provided to drive the roller A' in unison with the roller A, and the rolls B' in unison with the rolls B.

Below the rolls B' is a web guide 8 and adjacent this is an adjustable web guide 9 by which guides the longitudinally folded webs passing the former F' may be directed from rolls B' to rolls B; and there assembled with the webs passing the former F.

When such a press is operating at full capacity in the ordinary manner, and as heretofore necessary where it had but one folder, the webs w' and w^2 from the lower deck were led directly to roller A at the top of the former F, as shown in full lines in Fig. 1; and the webs w^3 and w^4 from the second deck; and webs w^5 and w^6 from the upper deck; were all led directly to the roller A; so that if the press was operating at full capacity 24 page book fold papers would be delivered by the folder. If such a press is equipped with my invention the webs can be assembled and papers delivered in book fold as described—or if desired the papers can be delivered in sections. In such case some of the webs instead of being led direct to roller A are led to the angle bars and diverted and passed to and over the former F' and after being longitudinally folded thereby are led back to the folding rolls B of the folder, and passed with the webs coming over the former F to the cutting and folding rolls C and D, and the product delivered in two sections.

For example if it is desired to produce 24 page papers in two sections, the webs w' , w^2 and w^3 could be led direct to roller A as indicated in full lines in Fig. 1; but the web w^4 would be led (as indicated by the dot-and-dash lines in Fig. 1) over guides 1^a and 1^b to angle bar 4, and diverted thereby at right angles to its normal lines of travel; then passed to and over angle bar 4^a, and directed into a path parallel with webs w' , w^2 and w^3 and led to the folder A' at the top of the former F'. Similarly web w^5 from the upper deck would be led over guides 1^c, 1^d and 1^e to angle bar 3; thence to angle bar 3^a, thence to the roller A' and assembled with web w^4 . Similarly web w^6 , instead of passing directly to roller A would be led over guides 1^f, 1^g and 1^h to angle bar 2, thence to angle bar 2^a; and then to the roller A', where it is assembled with the webs w^4 and w^5 .

The assembled webs (w^4 , w^5 and w^6) in

passing over former F' and between the first fold rolls B' are folded longitudinally and this group of longitudinally folded webs is then led under guide 8 and over guide 9 to and between the first fold rolls B of the folder, where they are assembled side by side with the group of webs (w', w² and w³), which had been led directly to roller A and folded longitudinally by the former F.

10 When the webs are led in the manner described the papers delivered from the folder will be in two sections of 12 pages each.

I have described the delivery of 24 page papers in two equal 12 page sections; but obviously if additional perfecting mechanism or additional decks are employed, papers of larger size and of greater variety can be produced.

With this invention a single page tubular press of any size can be made to deliver papers up to the full capacity of the press in either book fold or sections. Of course the size of the papers as a whole, and the number of pages in each section, can be varied according to the number of webs employed.

A press equipped with my invention can be conveniently and readily threaded by a pressman standing on the floor, as the web guides, angle bars and formers are easily accessible.

The auxiliary former F' and the angle bars 2^a, 3^a and 4^a can be arranged in line with the space at the side of the press which is required for proper access to the mechanisms of the press, and in order to plate and unplate the cylinders.

I claim:—

1. In combination; a single page tubular plate press having a folder adjacent one end 40 thereof and means for directing webs in a straight line from the press direct to the folder, to produce book fold papers; with an auxiliary former at one side of the press adjacent the former of the folder; angle bars 45 and web guides whereby part of the webs can be diverted and passed to the auxiliary former and longitudinally folded, and guides for directing such diverted longitudinally folded webs back to the folder to be assembled 50 with other webs passing direct to the folder to produce papers in sections.

2. In combination; a tubular plate press having a folder at one end of and in line therewith, said folder having a former, first fold 55 rolls, and cutting and delivery rolls; and guides for directing the webs from the press in a straight line to the former of said folder to produce book fold papers; with an auxiliary former arranged at one side of the press 60 adjacent the former of the folder; sets of angle bars and web guides whereby part of the webs coming from the press may be deflected and directed to and over the auxiliary former to be longitudinally folded thereby; 65 and guides whereby the longitudinally fold-

ed webs from the auxiliary former can be directed to the first fold rolls of the folder to be assembled with the other webs passing direct to the folder to produce papers in sections.

3. In combination; a tubular plate press 70 having a folder at one end of the press and in line therewith, said folder having a former, first fold rolls and cutting and delivery rolls; and guides for directing the webs from the press in a straight line to the former of said folder, to produce book fold papers; with an auxiliary former arranged at one side of the 75 press adjacent the former of the folder, a pair of first fold rolls adjacent the apex of the auxiliary former, sets of angle bars and web guides whereby webs coming from the press may be deflected and directed to and over the auxiliary former to be folded longitudinally thereby, and guides for directing the longitudinally folded webs from the folding webs 80 of the auxiliary former to the folding rolls of the folder to be assembled with the webs passing the folder former to produce papers in sections.
